(57) **CLAIM**

The ornamental design for a knife and associated sheath, as shown and described.

DESCRIPTION

FIG. 1 is a front perspective view of the knife and associated sheath shown in a first position of use, wherein a portion of the knife is located within the sheath;

FIG. 2 is a rear perspective view thereof;

FIG. 3 is a top plan view thereof;

FIG. 4 is a bottom plan view thereof;

FIG. 5 is a left elevation view thereof;

FIG. 6 is a right elevation view thereof;

FIG. 7 is a rear elevation view thereof;

FIG. 8 is a front elevation view thereof;

FIG. 9 is a perspective view of the knife and associated sheath shown in a second position of use, wherein the knife is spaced from the sheath;

FIG. 10 is a top plan view thereof;

FIG. 11 is a bottom plan view thereof;

FIG. 12 is a left elevation view thereof;

FIG. 13 is a right elevation view thereof;

FIG. 14 is a rear elevation view thereof;

FIG. 15 is a front elevation thereof;

FIG. 16 is a perspective view of the knife and associated sheath interconnected to a bracelet shown in a first position of use, wherein a portion of the knife is located within the sheath;

FIG. 17 is a top plan view thereof;

FIG. 18 is a bottom plan view thereof;

FIG. 19 is a left elevation view thereof;

FIG. 20 is a right elevation view thereof;

FIG. 21 is a rear elevation view thereof;

FIG. 22 is a front elevation view thereof;

FIG. 23 is a perspective view of the knife and associated sheath interconnected to a bracelet shown in a second position of use, wherein the knife is spaced from the sheath;

FIG. 24 is top plan view thereof;

FIG. 25 is a bottom plan view thereof;

FIG. 26 is a left elevation view thereof;

FIG. 27 is a right elevation view thereof;

FIG. 28 is a front elevation view thereof; and,

FIG. 29 is a rear elevation view thereof.

(Continued)

The broken line showing of the bracelet is provided for purposes of environment and forms no part of the claimed design. The blade and the end piece are depicted by broken lines because they illustrate elements of the knife and associated sheath that are not part of the claimed design.

1 Claim, 25 Drawing Sheets
